(57) **CLAIM**

The ornamental design for a thermal imaging camera, as shown and described.

DESCRIPTION

1. Thermal imaging camera

FIG. 1.1 is a top, front and right side perspective view of a thermal imaging camera according to the invention.

Fig. 1.2 shows a left side view of the thermal imaging camera of Fig. 1.1.

FIG. 1.3 is a top, front and left side perspective view of the thermal imaging camera of Fig. 1.1.

Fig. 1.4 shows a right side view of the thermal imaging camera of Fig. 1.1.

Fig. 1.5 shows a top view of the thermal imaging camera of Fig. 1.1.

Fig. 1.6 shows a front view of the thermal imaging camera of Fig. 1.1.

Fig. 1.7 shows a rear view of the thermal imaging camera of Fig. 1.1.

FIG. 1.8 is a top, rear and left side perspective view of the thermal imaging camera of Fig. 1.1.

FIG. 1.9 is a top, rear and right side perspective view of the thermal imaging camera of Fig. 1.1.
